The ornamental design for a power adapter for electric mats, as shown and described.

DESCRIPTION

FIG. 1 is a perspective view of a power adapter for electric mats, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The word "NAVIEN" is a registered trademark of KYUNG-DONG NAVIEN CO., LTD., which does not form part of the claimed design.
